UNITED STATES PATENT OFFICE

CHESTER J. DOLDING, OF DETROIT, MICHIGAN, ASSIGNOR TO MORGAN & WRIGHT, OF DETROIT, MICHIGAN, A CORPORATION OF MICHIGAN

DESIGN FOR A TIRE

Application filed January 5, 1927. Serial No. 20,282. Term of patent 14 years.

To all whom it may concern:

Be it known that I, CHESTER J. DOLDING, a citizen of the United States, residing at Detroit, county of Wayne, and State of Michigan, have invented a new, original, and ornamental Design for Tires, of which the following is a specification, reference being had to the accompanying drawing, forming part thereof, wherein—

Figure 1 is a plan view of a portion of a tire showing my new design; and

Figure 2 is a section of Figure 1 at 2—2.

I claim:

The ornamental design for a tire as shown.

Signed at Detroit, in the county of Wayne, and State of Michigan, this 30 day of December, 1926.

CHESTER J. DOLDING.
